UNITED STATES PATENT OFFICE.

FRANK E. MILLER, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

DISCHARGE-DOOR-OPERATING MECHANISM.

Application filed November 23, 1923. Serial No. 676,526.

This invention relates to railway dump cars and has for an object the provision of means for supporting and releasing a discharge door for one of such cars, which means comprises a plurality of members for supporting said door in its closed position and mechanism for moving said members out of their supporting positions with the door to allow the door to open, and which will permit these members to automatically move into their supporting positions with the door when the door is being closed, and which is also adapted to lock these members in their supporting positions when the door is closed.

Another object of the invention is to provide means for operating a plurality of discharge door supporting members and for locking these members in their door supporting positions.

These and other objects will be apparent from the following description.

Referring to the drawings in which like reference characters refer to like parts, Fig. 1 is a plan view of a portion of a railway dump car embodying the invention; Fig. 2 is a side elevational view of the same, the door operating and locking mechanism being shown in locked position; Fig. 3 is an enlarged side elevational view of the same, the mechanism being shown in its position to permit the discharge door to open by gravity; Fig. 4 is a like view showing the mechanism in position for permitting the automatic operation of the mechanism when the door is being closed and for supporting the door in closed position preparatory to locking the mechanism; Fig. 5 is an enlarged sectional view taken on the line 5—5 of Fig. 2; Fig. 6 is a sectional view taken on the line 6—6 of Fig. 4, and Fig. 7 is a like view of a modification of a portion of the invention.

Referring now in detail to the drawings, the reference character 1 indicates the side wall of a railway car and 2 indicates the discharge doors, which are preferably hinged to or adjacent the center sill 3 and have their free edges adjacent the side wall 1. Each of the doors 2 may be made of wood or metal and constructed in any preferred manner. Each of these doors is provided with strengthening members 4, each of which is preferably U-shaped in cross-section for

the greater part of its length and has a horizontal flange 5 which is secured to the door. These members extend outwardly beyond the free edge of the door and preferably beyond the side wall 1 and are adapted to be engaged by members 6 to support the door in closed position. The outer end portions of these members 4 instead of being U-shaped in cross section are provided with top portions 7 thus forming sockets for the reception of a bar or other suitable door closing means.

The members 6 are spaced apart and adjacent their upper ends are pivotally connected with bracket members 8 which are secured to the side wall 1. Each of these members 6 adjacent its lower end is provided with a ledge 9, the upper surface of which is adapted to engage with the lower surface of the outer end portion of one of the members 4 and when in such engagement these members will support the door in closed position. The pivot points of the members 6 are so located that these members will, after they have been moved out of engagement with the members 4, move by gravity to their proper door supporting positions. There are two members 6 for each discharge door, which members are spaced apart and when operated preferably move in opposite directions. Between these members a stationary member 10 is provided which is secured to the side wall 1 which member is provided with an outwardly extending T-shaped projection 11 on which a member 12 is slidably mounted. This member 12 is provided with an opening 13 which is adapted to receive the projection 11 and when the members are in their operative positions it will be noted that they will be so interlocked that they will not become accidentally separated and yet free movement of the member 12 relative to the member 10 will be permitted. The member 12 is provided with a projection 14 on which the inner end portions of links 15 are pivotally mounted the outer end portion of each link being pivotally connected with one of the members 6. The member 12 is also provided with stop shoulders 16 which are adapted to engage with stop shoulders 17 on the member 10 to prevent the member 12 from moving downwardly an excessive distance. When the stop shoulders 16 are in engagement with the stop

shoulders 17 the lower end portion of the member 12 extends some distance below the member 10 and forms a striking block which may be struck by a sledge or other suitable tool to open the door.

The projection 14 of the member 12 on which the inner ends of the links 15 are mounted, is so located that when the members 6 are in their door supporting positions 10 and the stop shoulders 16 and 17 are in engagement with each other as shown in Fig. 2 of the drawings, the axis of the projection will be in a position below a line drawn through the axis of the members connecting 15 the links 15 and the members 6. In other words, the center of the projection is below a straight line drawn through the center of the connections between the links 15 and members 6, thus locking the members 6 in 20 their door supporting positions.

The member 12 is provided with a dog 18 which is pivotally mounted on a projection on the member 12 which projection in the present embodiment of the invention is in 25 the form of a pin 19. This dog 18 is adapted to engage the top surface of a projection 20 formed on the member 10 and when in such engagement will support the links 15 and member 12 in the position as shown in Fig. 4 30 of the drawings in which position it will be noted the axis of the projection 14 will be above the axes of the connections between the links 15 and members 6 and that the members 6, links 15 and member 12 are 35 automatically movable as the discharge door is being moved to closed position. To permit the links 15 and member 12 to move from their positions as shown in Fig. 4 of the drawings to their locked positions as shown 40 in Fig. 2, the dog 18 is moved outwardly to the position as shown in Fig. 5, free of the projection 20, which permits the member 12, dog 18 and inner ends of the links 15 to move downwardly until the shoulders 16 engage 45 the shoulders 17 at which time the several parts of the mechanism are in their locked positions. It will here be noted that the projection 20 is spaced away from the member 12 a distance sufficient to permit the dog 50 18, when it is in the position as shown in Fig. 5 to move downwardly with the member 12 as such member is moved to locked position.

To hold the mechanism in locked position 55 against accidental movement the cam surface 21 of the dog 18 engages the under surface of the projection 20 and will thus prevent the member 12 and links 15 from moving upwardly to locked positions. It will be seen 60 from Fig. 6 of the drawings that if it is not desired to prevent accidental movement of the member 12 and links 15, the lower portion of the projection 20 may be so formed that the dog will not engage with it to hold 65 the mechanism against accidental movement.

Assuming the door to be in closed position as illustrated in Figs. 1, 2, and 5 and it is desired to open it, the operator moves the dog 18 out of engagement with the underside of the projection 20 and then strikes the 70 lower end of the member an upward blow with a sledge, causing the member 12, dog 18 and adjacent ends of the links 15 to move upwardly, which in turn causes the members 6, through the medium of the links 15, to be pulled toward each other and out of engagement with the end portions of the members 4 secured to the door 2 at which time the door will be released and will move 75 downwardly to its open position. As the member 12 is being moved upwardly the dog 18, after it has been moved above the projection 20, will move automatically inwardly into the plane of the projection 20. After the door has been released the member 80 12 and dog 18 will move downwardly by gravity until the dog engages the top surface of the projection 20 and when in such engagement will support the member 12 and links 15 in the positions as shown in Figs. 85 4 and 6 of the drawings. As the member 12 moves downwardly the members 6 move automatically to door supporting positions, 90 as shown in Fig. 4.

To close the door the operator inserts a 95 bar or other suitable device in the end portion of one of the members 4 and by the use of such bar raises the door until the tops 7 of the members will engage the lower bevelled surfaces 23 of the members 6 and a continued upward movement of the door will cause the members 6 to move toward each other and out of the path of the ends of the members 4 until such time as the door is 100 closed at which time the members 6 will move automatically to their door supporting 105 positions as shown in Fig. 4. When the links are operating in the manner just described the member 12, dog 18 and inner ends of the links 15 move automatically upwardly and downwardly the downward movement being limited by the dog 18 engaging the top surface of the projection 20. After the door has been closed and the mechanism is in the position as shown in 110 Fig. 4 of the drawings the operator moves the dog 18 outwardly to a position free of the top surface of the projection 20 which permits the member 12, dog 18 and inner ends of the links 15 to move automatically 115 downward until such movement is stopped by the shoulders 16 on the member 12 engaging the shoulders 17 on the member 10, thus automatically locking the members 6 in 120 their door supporting positions. As the shoulders 16 engage the shoulders 17 the dog 18 will automatically engage the lower 125 surface of the projection 20 and will hold the member 12 and connected parts against 130 accidental upward movement.

In cases where the dog 18 is not used to prevent accidental movement of the mechanism when such mechanism is in locked position, Fig. 7, the operator in opening the door does not have to first move the dog before striking the member 12, but may first strike the member 12 and the operation of the dog during the operation of the mechanism will be entirely automatic up to the time it is desired to lock the members in closed position when the dog is moved by the operator from the ledge 20 and the links drop to locking position.

It will be apparent to those skilled in the art to which this invention appertains that changes may be made in the form and arrangement of the several parts of the mechanism without departing from the spirit and scope of the appended claims.

20 I claim:

1. In a dump car, a discharge door, a plurality of members pivotally mounted on the car body, adapted to support said door in its closed position, means for moving said members out of their door supporting positions, and means whereby simultaneous movement of said members is insured, the first mentioned means being adapted by gravity to automatically lock said members in their door supporting positions.

2. In a dump car, a discharge door, a plurality of members pivotally mounted on said car adapted to be moved into and out of supporting positions with said door, and means connected with said members and with said car for operating said members, said means being adapted by gravity to automatically lock said members in door supporting positions.

3. In a dump car, a discharge door, a plurality of members pivotally mounted on said car adapted to be moved into and out of supporting positions with said door, means for moving said members out of door supporting positions, and means for insuring the simultaneous movement of said members, said means being adapted to permit said members to move automatically into supporting position with the door when the door is closed and to automatically lock said members in supporting positions with said door.

4. In a dump car, a discharge door, members movable into and out of supporting positions with said door, a vertically movable member between said members, links pivotally connected with said members and vertically movable member, the axis of the connection between said vertically movable member and said links being adapted to

move below the horizontal plane of the axes of the connections between said links and members to lock said members in their door supporting positions.

5. In a dump car, a discharge door, movable door supporting members, a vertically

movable member between said members, links pivotally connected with said vertically movable member and said members, the center of the connection between said vertically movable member and links being adapted to be held above the centers of the connections between said door supporting members and links, to permit the automatic operation of said door supporting members as the door is being closed and adapted to be moved to a position below said centers to lock said door supporting members when the door is closed.

6. In a dump car, a discharge door, a plurality of pivotally mounted door supporting members, mechanism for moving said members out of the door supporting positions, said mechanism embodying means for maintaining said mechanism in a position whereby said members are movable automatically into door supporting positions when the door is being closed, said means being releasable to permit said mechanism to automatically lock said members in their door supporting positions, and means connected with said car and mechanism, whereby simultaneous movement of said members is insured.

7. In a dump car, a discharge door, a plurality of connected pivotally mounted members, movable into and out of supporting positions with said door, mechanism for operating and automatically locking said members when said door is closed and means connected with said car and mechanism for guiding said mechanism as it is operated.

8. In a dump car, a discharge door, members pivotally mounted on said car, adapted to be moved into and out of supporting positions with said door, link members for locking said members in their door supporting positions, and means on said car for guiding said link members.

9. In a dump car, a discharge door, members pivotally mounted on said car, adapted to be moved into and out of supporting positions with said door, and means for operating and locking said members, said means comprising links connected with each other and with said members and with the car.

10. In a dump car, a discharge door, members pivotally mounted on said car, adapted to be moved into and out of supporting positions with said door, links slidably mounted on said car and operatively connected with said members and with each other, adapted to lock said members in their door supporting positions.

11. In a dump car, a discharge door, members pivotally mounted on said car adapted to support said door in its closed position, a member movably mounted on said car, connections from said member to said members, said member and connections being adapted to lock said members in their door

115

120

125

130

- supporting positions and being adapted to be moved to unlocked positions and move said members out of their door supporting positions, and means whereby said members 5 are rendered automatically operable to their door supporting positions after the door has been released.
12. In a dump car, a discharge door, members pivotally mounted on said car, adapted 10 to be moved into and out of supporting positions with said door, and mechanism for operating said members, said mechanism comprising a member movably mounted on said car, links therefrom to said members, 15 connections between the links and member being adapted to be held at one side of the horizontal plane of the connections between said links and members whereby said members are permitted to automatically move to 20 their door supporting positions when the door is open and when it is being closed, said connections between the links and members being movable to the opposite side of the horizontal plane of the connections be- 25 tween the links and members for locking said members in supporting positions with said door.
13. In a dump car, a discharge door, members movable into and out of supporting po- 30 sitions with said door, mechanism for moving said members out of supporting positions with said door to open said door, and to permit said members to automatically move into supporting position with said door 35 when the door is being closed and to lock said members in their door supporting positions when the door is closed, said mechanism embodying a movable connection with the car.
14. In a dump car, a discharge door, mem- 40 bers movable into and out of supporting positions with said door, means movably connected with the body of said car for operating said members, and means whereby a certain downward movement of the first 45 mentioned means will cause said members to be locked in their supporting positions with said door when it is closed.
15. In a dump car, a discharge door, mem- 50 bers movable into and out of supporting positions with said door means for operating said members, said means in one position being adapted to permit the automatic operation of said members and in another position being adapted to lock said mem- 55 bers in their supporting positions with said door, and a movable connection between said means and car.
16. In a dump car, a discharge door, mem- 60 bers movable into and out of supporting po- sitions with said door, means slidably connected with the body of said car for operating said members, said means being movable to different positions to permit the automatic operation of said members and to lock said members in their supporting positions with said door when said door is closed.
17. In a dump car, a discharge door, mem- 65 bers movable into and out of supporting po- sitions with said door, connected links for 70 operating said members, the connection be- 75 tween said links being movable to a position whereby said members are held by the links in their supporting positions with said door, and guiding means for said links mounted on said car when it is closed.
18. In a dump car, a discharge door, mem- 80 bers movable in opposite directions to each other into and out of supporting positions with said door, common means comprising a pair of links movable relative to each other for both operating and locking said mem- 85 bers, and means associated with the first mentioned means and car for insuring simultaneous movement of said members.

In testimony whereof I affix my signature.

FRANK E. MILLER
